Primary Examiner — Lauren D McVey(57) **CLAIM**

The ornamental design for a printer, as shown and described.

DESCRIPTION

FIG. 1 is a front, top and left side perspective view of a printer showing my new design;

FIG. 2 is a rear, top and right side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of a portion defined by lines 9-9 in FIG. 3.

The evenly spaced broken lines that are immediately adjacent to the claimed areas and define unshaded regions depict the bounds of the claimed design, while all other evenly spaced broken lines are directed to environment. In addition, the dot-dash arrows in FIG. 3 are for reference purposes only and form no part of the claimed design.
